OPPOSED PISTON SLEEVE VALVE OUTBOARD MOTOR

John Stucke, Philadelphia, Pa.

Application September 1, 1953; Serial No. 377,869

2 Claims. (Cl. 123—51)

This invention relates to an opposed piston sleeve valve outboard motor for use in connection with a small boat and specifically provides a compact, dependable and novel construction of an opposed piston sleeve motor.

An object of this invention is to provide an opposed piston sleeve valve outboard motor wherein the propeller driven thereby is reversible and the motor and propeller are adjustable about a mounting clamp on a vertical and a horizontal axis.

Another object of this invention is to provide an outboard motor having a pair of crankshafts, a connecting shaft therebetween, a common cylinder assembly between said crankshafts and opposed pistons thereon for imparting power impulses to the crankshafts, and means for driving a propeller on the housing of the motor.

A further object of this invention is to provide a novel rotary sleeve valve arrangement for the opposed piston motor wherein the sleeve valve has a single opening that sequentially matches with openings in the cylinder, thereby providing the intake, ignition and exhaust of the combustible mixture.

Yet another object of this invention is to provide a novel exhaust system wherein the exhaust gases are discharged under the water line and below the tips of the propeller, wherein the action of the propeller assists in the scavenging of the cylinder chamber and the particular location assures a discharge of the exhaust gases beneath the water line when the boat is in operation.

A still further object of this invention is to provide an opposed piston sleeve valve outboard motor which has an oil reservoir and an oil pump for supplying pressurized oil to the various rotational parts of the motor and further provided with means for rotating the crankshafts for starting the motor and a magneto for supplying ignition current to suitable spark plugs.

Still another object of this invention is to provide a motor for the purposes described which is compact in construction, efficient in operation, requires a minimum of maintenance, and inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side, elevation section view taken substantially along the center line of the outboard motor of this invention showing the details of construction of the cylinder assembly and drive mechanism;

Figure 2 is a transverse, top plan section taken substantially along section line 2—2 of Figure 1 showing details of the crank eccentric and housing therefor;

Figure 3 is a perspective detail of the rotary sleeve valve member showing the single oblong opening therein and the drive means therefor;

Figure 4 is a perspective detail view showing the liner for the cylinder and showing two of the three openings therein;

Figure 5 is a transverse, vertical section taken substantially along section line 5—5 of Figure 4 showing the three openings about the periphery of the cylinder liner;

Figure 6 is a perspective view of the remote control plate for the reversing mechanism of the propeller drive means;

Figure 7 is a detail schematic view showing the pistons in opposed relation at their innermost points at the end of the compression stroke wherein the spark plug is in communication with the interior of the combustion chamber and ready to ignite the combustible mixture;

Figure 8 is a transverse, vertical section taken substantially along the section line 8—8 of Figure 7, showing the particular arrangement of the rotary sleeve valve and the spark plug as the spark plug is ready to fire;

Figure 9 is a view similar to Figure 7 with the pistons at the end of the power stroke and the opening in the sleeve valve about to communicate with the exhaust opening in the cylinder;

Figure 10 is a transverse, vertical section taken along section line 10—10 of Figure 9 showing the relative position of the rotary valve and the direction in which the valve rotates;

Figure 11 is a view similar to Figure 7 showing the pistons as they move inwardly to exhaust the burned gases;

Figure 12 is a transverse, vertical section taken substantially along section line 12—12 of Figure 11 showing the arrangement of the rotary valve aperture in alignment with the exhaust opening in the cylinder, permitting the exhaust of the burned gases;

Figure 13 is a view similar to Figure 7 showing the pistons at the end of the intake stroke; and,

Figure 14 is a transverse, vertical section similar to Figure 12 showing the location of the sleeve valve aperture after the completion of the intake stroke and progressing to a beginning of the cycle.

Referring now more specifically to Figure 1 of the drawings, it will be seen that the numeral 10 generally designates the opposed piston sleeve valve outboard motor of this invention for driving a suitable propeller 12 and having a clamp means 14 for attaching the motor 10 to the stern plate of a suitable small boat (not shown).

As clearly shown in the drawings, the motor 10 includes a unitary cylinder and housing 16 having projecting cooling fins 18 about the periphery thereof, and suitable crankcase members 20 projecting therefrom at its remote ends. Rotatably mounted in each of the crankcase portions 20 is a crankshaft 22 having an eccentric 24 thereon, and suitable flywheels 26 for rotation therewith, wherein said crankshaft 22 is journaled in the crankcase members 20 by suitable bearings 28. A piston 32 having suitable rings 34, and connecting rods 36 and connecting rod bearing 38, is journaled on the eccentric 24 for reciprocable movement in the piston housing 16.

As will be seen in Figure 1, the piston 32 is operatively connected to each of the crankshafts 22 wherein the pistons 32 will be reciprocated in the cylinder 16 upon rotation of the crankshafts 22 in an obvious manner. Still looking at the upper portion of Figure 1, it will be seen that the two crankshafts 22 are interconnected by a connecting or lay shaft 40 having a bevel gear 42 on remote ends thereof for engaging bevel gears 44 and 46 on the upper ends of the crankshafts 22. The lay shaft 40 is journaled in suitable bearings 48 in an upstanding portion of the cylinder housing 16 and adjacent the midpoint of the lay shaft 40, a fan member 50 is secured thereto and rotatable therewith for circulating air over the periphery of the cylinder housing 16. Projecting from one end of the lay shaft 40 is an auxiliary driving shaft 52 operatively connected to a magneto 54 which is suitably supported by a fastening means 56. Adjacent

70

the lower end of crankshaft 22 which is adjacent the magneto 54 is an oil reservoir 58 secured to the housing 16 by suitable bolts 60 and an oil pump 62 is secured to the bottom of the reservoir by suitable bolts 64 and driven by a shaft 66 having oppositely directed lugs 68 thereon for engaging in oppositely disposed slots 70 in the end of crankshaft 22. Oil 72 is taken from the reservoir 58 and pumped by the pump 62 out through a suitable discharge line 74 which has suitable connections to the various wear points throughout the motor. Projecting upwardly from the other of the crankshafts 22 is an extending portion with a V-belt pulley 76 thereon for the reception of a starting rope (not shown) for rotating the crankshafts and starting the motor by the usual pulling of the starting rope, as is well known. As best shown in Figure 2, each of the crankcases 20 is formed from a separable element forming a pan member 78 which is secured to the crankcase 20 by suitable bolts 80 wherein the pan 78 may be removed from the crankcase 20, thereby permitting repair and maintenance of the crankshaft and connecting rod assembly. A cover 82 having suitable apertures 84 therein is positioned over the lay shaft 40 by suitable fastening means 86, thereby protecting the mechanism and also affording apertures for circulating air. A sleeve valve 88 is rotatable in the cylinder housing 16, and held in non-reciprocable movement relative thereto by a ring member 90 on one end engaging the outer edge of the cylinder housing 16 and a ring gear 92 engaging the other end of the cylinder housing 16, and the ring gear 92 is driven by a spur gear 94 secured to the lay shaft 40 through an idler gear 96 having a suitable journal 98 secured to the housing 16. The relative sizes of gears 94 and 96 and ring gear 92 is such that the rotary valve 88 will communicate with the various openings in the cylinder housing 16 to sequentially permit intaking of the combustible mixture, ignition of the combustible mixture and exhausting of the burned gases in a manner hereinafter described.

It will be seen that a hollow elongated housing 100 is secured to the crankcase 20 by suitable bolts 102 and a lower end of the crankshaft 22 is housed within the upper portion of this tubular housing 100. The end of the crankshaft which depends into the hollow tubular member 100 has a blind bore forming a socket 104 therein with suitable splines 106 on the internal surface thereof. Slidably received in the bore 106 is a projecting extension 108 concentric with and driven by the crankshaft 22, and the shaft 108 is suitably journaled in a plate 110 adjacent the lower end of the tubular housing 100. Adjacent the lower end of the shaft 108 is mounted an upper bevel gear 112 and a lower bevel gear 114 in facing relation to each other, and between the upper bevel gear 112 and the socket member 104 is a coil compression spring 116 for urging the shaft 108 downwardly. Journaled in one side of the tubular housing 100 is a stub shaft 118 having a bevel gear 120 thereon in engagement with the bevel gear 112 in its normal operating position. Secured to the stub shaft 118 is the propeller 12 by suitable screw threaded fastening means 122, and as the blades of the propeller rotate, the motor and the boat will be propelled through the water in an obvious manner. As will be seen, a portion of the extending shaft 108 extends through the plate 110 and forms a shaft lifting member 124 which is rotatable in a socket 126 in the end of the shaft 108 and suitable thrust bearings 128 take up the thrust when the shaft 108 is lifted against the action of coil spring 116. Pivotaly mounted on the inner walls of a propeller protecting member 130 is a member 132 which engages the shaft lifting member 124 and the member 132 is pivoted to the protector 130 by a suitable pivot 134 at one end and engaged by a Bowden cable 136 at its other end and the Bowden cable 136 extends along the inner periphery of the housing 100 and out through a

5 suitable opening 138 adjacent its upper end and proceeds to a remote control 140 for reversing the propeller 12. As the shaft 108 is lifted, the lower bevel gear 114 engages the bevel gear 120 on the stub shaft 118, thereby turning the propeller 12 in a reverse direction.

As best seen in the lower right hand section of Figure 1, the remote control means 140 has an axle member 142 with the handle 144 secured thereon and rotating the same, and a crank lever 146 secured to one end of the axle 142 and having suitable fastening means 148 for attaching to the inner wire 150 of the Bowden cable, wherein upon rotation of the axle 142, the Bowden cable inner wire 150 is moved, thereby raising the lift member 124 and disengaging the bevel gear 112 and engaging the bevel gear 114 with the bevel gear 120. As will be obvious, the plate 140 may have a suitable slot therein showing the reverse position 152, the forward position 154, and a neutral position 156 in the usual manner. As best seen in the central portion of Figure 1, the cylinder housing 16 has an exhaust opening 158 and a tubular passage 160 is connected thereto and communicates with the tubular housing 100, and a suitable exhaust discharge 162 is in communication with the tubular housing 100, thereby providing discharge of the 10 exhaust gases. It will be noted that the discharge 162 is located below the tip of the propeller 12, thereby assuring that the exhaust is below the water line and also, due to the action of the blade of the propeller 12, the suction will assist in the scavenging of the exhaust gases from the cylinder 16. Secured to the undersurface of passage 160 is a pair of pivotally mounted plates 164 in the nature of a hinge having a suitable hinge pin 166. One of the plates 164 is rigidly attached to the undersurface of the passage 160, and the other plate is provided with an adjusting screw 168 for adjusting the angular relationship of the plates 164. Rigidly secured to the undersurface of the lower of the plates 164 is a depending rod 170 received in a suitable elongated socket 172 for rotation therein, and a suitable set screw 174 is threaded into the side of the socket and engages the rod 170 for precluding rotation thereabout. Secured to one side of the socket 170 is a suitable clamp 176 having a screw threaded member 178 in one of the legs of the clamp, and a suitable handle 180 is positioned at the remote ends of the screw threaded member 178 for actuating the boat engaging pads 182, thereby clamping the motor 10 to the stern board of a boat in an obvious manner. As appears obvious, the clamp 176 is attached by manipulating the handles 180 and by suitable manipulation of the set screw 174 and the adjusting screw 168, the motor 10 may be adjusted about the longitudinal axis of the rod 170 which will be substantially vertical in its normal operation in about the axis of the hinge pin 166, which is substantially horizontal in its normal operating position. It will be noted that the hinge 164 is free to pivot in one direction, thereby providing a safety feature if the protector 130 hits an object, the motor will immediately pivot about axis 166 preventing any undue damage to the propeller and driving mechanism.

Referring now more specifically to Figures 3-5, it will be seen that the sleeve valve 88 is provided with a single oblong-shaped aperture 184 at its midpoint between the ring gear 92 and the flange 90. It will be seen that the ring gear 92 is integral with the sleeve valve 88 and the flange 90 is secured thereto by a suitable fastening means 186 wherein the sleeve valve may be taken out by the cylinder 16. As best seen in Figure 4, the cylinder 16 is provided with a liner 188 which is rigid with the cylinder housing 16 and non-movable in relation thereto. The liner 188 has a plurality of square apertures, with one of said apertures 190 being in registry with the exhaust opening 158 and the other openings 192 and 194 are in registry with a spark plug 196 and its mounting

means 193, and an inlet port 200, respectively, as best shown in Figures 7-14.

Referring now more specifically to Figures 7-14, the operation of the device will be readily understood. As the pistons 32 move together during the compression stroke, the combustible mixture is compressed, and the cylinders 32 partially cover the aperture 184 in the valve 88, and the spark plug 196 ignites the mixture with the proper spark from the magneto 54 and the pistons 32 are forced apart during the power stroke, thereby rotating the crankshaft 22 and driving the propeller 12, oil pump 62 and magneto 54 as well as rotating the valve 88. As the end of the power stroke is reached, the aperture 184 comes into registry with the exhaust passage 158, thereby exhausting the burned gases out through passage 160 and opening 162. Due to the weight of the flywheels 26, the inertia of the piston assembly, the pistons 32 again approach each other on the exhaust stroke, and again expand on the intake stroke when the aperture 184 is in registry with the inlet port 194, thereby taking a fresh charge of combustible mixture into the combustion chamber. This sequence of operation is substantially the same as the standard four-cycle motor.

As the crankshafts 22 rotate, the pinion gears 46 and 42 are in meshing engagement, and the lay shaft or connecting shaft 40 transmits the power of the right hand crankshaft 22 to the left hand crankshaft 22, thereby utilizing all of the power in the driving of the propeller 12 through the extension shaft 108 in an obvious manner. Obviously, some of the power of the shaft 22 is used to turn the pump 62 and the magneto 54, and certain frictional losses are incurred in the usual bearings 28 and 48. When it is desired to reverse the propeller 12, the handle 144 is moved from the forward to the reverse position, and the Bowden cable 136 with the internal wire 150 actuates the lift member 132 and the member 124 for raising the slideable shaft 108, thereby disengaging the bevel gear 112 from the bevel gear 120 and engaging the reverse bevel gear 114 with the bevel gear 120, thereby driving the stub shaft 118 and the propeller 12 in reverse direction. All the motor is provided with a suitable housing, such as the cover 82, for protecting the operator from all moving parts and for providing a pleasing appearance. It will be noted that any oil fumes passing through the combustion chamber and out through the exhaust passage 160 will help to lubricate the bevel gears 112 and the bearings 128 prior to its passage through the opening 162 into the atmosphere.

The increase in power and relative power to weight ratio of this type engine as utilized in the specific construction and arrangement of various parts and the various safety features and adjustable features inherent in this construction provide a highly satisfactory and efficient outboard motor. The various components of the device may be made of any suitable material which is well known in the industry and meets the requirements of the particular element.

From the foregoing, the construction and operation of the device will be readily understood and further explanation is believed to be unnecessary. However, since numerous modifications and changes will readily occur

to those skilled in the art, it is not desired to limit the invention to the exact construction shown and described, and accordingly, all suitable modifications and equivalents may be resorted to, falling within the scope of the appended claims.

What is claimed as new is as follows:

- An internal combustion engine comprising a cylindrical housing, a pair of spaced parallel crankshafts with a crankshaft being disposed in transverse relation at each end of the housing, a pair of opposed pistons reciprocably received in said housing and operatively connected to said crankshafts, a rotary sleeve valve mounted in said housing and receiving said pistons, a lay shaft interconnecting said crankshafts for simultaneous rotation thereof, said rotary valve having a single opening disposed centrally therein, said cylindrical housing having a plurality of circumferentially spaced openings in the same transverse plane as the opening in the valve, and means interconnecting said lay shaft and rotary sleeve valve for rotating said valve in timed relation to the crankshafts and pistons for sequential registry of the opening in the valve with the openings in the cylindrical housing for intake, ignition and exhaust of a power producing mixture.
- An internal combustion engine comprising a cylindrical housing, a pair of spaced parallel crankshafts with a crankshaft being disposed in transverse relation at each end of the housing, a pair of opposed pistons reciprocably received in said housing and operatively connected to said crankshafts, a rotary sleeve valve mounted in said housing and receiving said pistons, a lay shaft interconnecting said crankshafts for simultaneous rotation thereof, said rotary valve having a single opening disposed centrally therein, said cylindrical housing having a plurality of circumferentially spaced openings in the same transverse plane as the opening in the valve, and means interconnecting said lay shaft and rotary sleeve valve for rotating said valve in timed relation to the crankshafts and pistons for sequential registry of the opening in the valve with the openings in the cylindrical housing for intake, ignition and exhaust of a power producing mixture, one of the openings in the cylindrical housing having a spark plug disposed therein for igniting the compressed power producing mixture as the opening in the rotary sleeve valve is in registry with the spark plug.
